UNITED STATES PATENT OFFICE.

ROBERT P. DE REMER, OF HOUMA, LOUISIANA, ASSIGNOR OF ONE-HALF TO ALFRED T. GERRANS, OF HOUMA, LOUISIANA.

WOODWORKING-MACHINE.

No. 890,583.

Specification of Letters Patent.

Patented June 9, 1908.

Application filed October 21, 1907. Serial No. 398,496.

To all whom it may concern:

Be it known that I, ROBERT P. DE REMER, a citizen of the United States of America, residing at Houma, in the parish of Terrebonne and State of Louisiana, have invented certain new and useful Improvements in Woodworking-Machines, of which the following is a specification.

This invention relates to wood working machines, and the object thereof is to provide a machine of such class in a manner as hereinafter set forth particularly adapted for cutting Gothic heads on fence pickets and posts, and is furthermore adapted for cutting round ends on the butts of shingles.

A further object of the invention is to provide a machine of such class with adjustable means in a manner as hereinafter set forth whereby heads of different contour can be cut.

Further objects of the invention are to provide a machine for the purpose set forth which shall be simple in its construction, strong, durable, efficient in its use, readily set up and comparatively inexpensive to manufacture.

With the foregoing and other objects in view, the invention consists in the novel construction, combination and arrangement of parts hereinafter more specifically described and illustrated in the accompanying drawings, wherein is shown the preferred embodiment of the invention; but it is to be understood that changes, variations and modifications can be resorted to which come within the scope of the claims hereunto appended.

In describing the invention in detail reference is had to the accompanying drawings wherein like characters denote corresponding parts throughout the several views, and in which—

Figure 1 is a side elevation of a wood-working machine in accordance with this invention; Fig. 2 is a top plan view; Fig. 3 is a transverse section; Fig. 4 is a detail in side elevation showing the position of the picket in full lines just prior to the cutter acting thereon and in dotted lines one-half of the head formed; Fig. 5 is a side view of the picket showing completed head.

Referring to the drawings in detail, 1 denotes the machine frame which is formed of a series of longitudinal, vertical and transverse bars, and, journaled, as at 2, in the top 55 of the frame is a driven shaft 3, connected by

the pulley 4 with a prime mover (not shown). The shaft 3 constitutes the operating shaft for the cutter, the latter being indicated by the reference character 5 and embodying a pair of collars 6, which are fixed to the shaft 3 and to which are attached a pair of knives 7, 8, the former extending in an opposite direction with respect to the latter and said knives being so positioned as to obtain the necessary clearance during the operation of the cutter upon the picket 9. The cutter 5 is mounted upon the shaft 3 at one side of the frame 1 and for this purpose the shaft 3 projects laterally from said frame.

One side of the machine frame is provided with two pairs of uprights. The uprights of one pair are indicated by the reference characters 10 and 11 and the uprights of the other pair are indicated by the reference characters 12 and 13. The uprights 11 and 12 are the outer uprights, the latter being of greater length than the former. The uprights 10 and 13 are flush with the top of the frame, while the upright 12 projects above the top of the frame and carries near its upper end a pulley 14. The upright 11 also projects above the top of the frame, but not to the extent of the upright 12. Each of the uprights 10, 11, 12 and 13 is formed with a vertically-extending opening 15, and to the outer faces of the uprights 11 and 12, and directly in front of the opening 15 is positioned a slotted plate 16, the lower end of the plate being secured in position by the holdfast devices 17. Against the inner faces of the uprights 10 and 13 at the rear of the opening 15 of said uprights is positioned a slotted plate 18, the lower one being secured to its respective upright by the holdfast device 19. The upper ends of the plates 16 and 18 are secured together by the holdfast devices 20. Extending through each pair of plates 16, 18 is a headed bolt 21, which is fixed in position by the clamping nut 22. Each of the bolts 21 also carries a washer 23 which is positioned in advance of the plate 16.

Arranged at one side of the machine frame 1 is a work-holder adapted to be swung towards the cutter 5 so that the work will be brought into proximity to the cutter to allow of the operation of the latter upon the work so as to form the head. The work holder which is angular in cross section has the horizontal portion thereof indicated by the reference character 24 and the vertically-

extending portion by the reference character 25. The vertically-extending portion 25 is bifurcated as at 26, 27 and extending between the furcations is the upper end of a 5 link 28, the said upper end being pivotally connected, as at 29, to the vertically-extending portion 25 of the work holder. The said vertically-extending portion is cut away so that one of the furcations of each bifurcated 10 portion is shorter than the other, as at 30, constituting abutments adapted to engage the stops 31 carried by the uprights 11 and 12, the said stops 31 limiting the movement in one direction of the holder—that is to say, 15 towards the cutter. The links 28 extend in parallelism with respect to the plates 16 and each of said links 28 is formed with a series of openings 32 which register with the openings 33 in the plates 16, the openings 33 registering with the openings 34 in the plates 18. The links 28 are adapted to be mounted upon 20 the bolts 21 between the heads 35 of the bolts 21 and the washers 23. The links 28 swing upon the bolts 21 and the length of the links 25 is such with respect to each other that the work holder is maintained when elevated at the same level throughout; but to allow of the work holder swinging upon different arcs so as to change the contour of the head cut upon 30 the picket, the bolts are adapted to be shifted so as to extend through the sets of alining openings between the links and plates. If the bolts 21 are positioned at the lower ends of the links and plates the extent of movement 35 of the work holder will be greater than if the bolts 21 were positioned at the center or top of the links and plates, but the arc in which the work holder travels would be less, and by such an arrangement the length and 40 contour of picket heads can be varied as will be evident for the reason that if the work holder moves upon a small arc the length of the head cut will be shorter than it would be if the work holder moved through a greater 45 arc.

The horizontal portion 24 of the work holder near that end which is arranged in proximity to the cutter 5 is provided upon its upper face with a resilient member 36 50 having one end fixed by the holdfast devices 37 to the work holder and its free end bent in an angular manner, as at 38 and sharpened. Extending through the portion 24 of the work holder is an adjusting screw 39 55 adapted to bear against the free end of the member 36 so as to enable the elevating of said member when occasion so requires. The function of the angular end 38 of the member 36 is to bite in the work to prevent 60 the same from being drawn off the work holder when the work is operated upon by the cutter. The horizontally-extending portion 24 of the work holder is formed with a plurality of screw-threaded sockets 40 which 65 are adapted to receive a set-screw 41 carry-

ing a nut 42. Interposed between the nut 42 and mounted upon the set screw 41 is an adjustable stop 43 having an elongated slot 44. The sockets 40, set screw 41, nut 42, stop 43 provide means for positioning the 70 work with respect to the holder—that is to say it enables the length of that portion of the work which projects from the holder to be varied and at the same time enables uniformity in the length of the head cut upon 75 the work. The adjustable stop 43 associates with the angular end 38 of the member 36 in this particular; if the work is brought against the stop and pressure applied upon the work it will cause the angular end 38 to bite into 80 the work and assist in maintaining one end of the work against the stop.

Connected to the rear end of the work holder and passing over the pulley 14 is a flexible member 45 which extends through 85 an opening 46 formed in the side of the frame 1 at the top thereof and also passes over a pulley 47 secured in said opening through the medium of the keeper 48. The lower end of the member 45 carries a counter-balance 90 weight 49, the function of which is to constantly pull the work holder in a direction towards the cutter. A stop 50 is secured to the side of the frame 1 for limiting the downward movement of the work holder when it is 95 moved away from the cutter.

The work holder having been adjusted so that when shifted it will move in the arc desired, and the work having been placed upon the work holder, the latter being in the depressed position as shown in full lines in Fig. 4, the operator holding the work holder in such position (which is contrary to the position that the work holder assumes when the weight is free to act) the operator now shifts 100 the holder towards the cutter. Such action is had with the assistance of the weight 49. The position which the work holder assumes with the work after it has been shifted to an operative position with respect to a cutter 110 is shown in dotted lines in Fig. 4. After the cut has been made upon one side of the work, the holder is shifted rearwardly and the work is then turned to position the other side thereof which is to be cut and the holder is 115 then shifted manually towards the cutter by the operator so that the holder will assume the position shown in dotted lines in Fig. 4 when the work will be again cut.

What I claim is—

1. A wood working machine comprising a frame; a plurality of transversely extending knives fixed to a rotatable head, a rotatable and transversely extending shaft carrying said head, a longitudinally extending and 125 longitudinally and vertically shiftable work holder arranged in operative relation with respect to said knives, a plurality of links pivotally connected at their upper ends to said holder, the apertures in one link being 130

in alinement with the apertures in the other link, a plurality of apertured plates carried by the frame, the apertures in said plates being in alinement with the apertures in the 5 links, and an adjustable means extending through the links and plates for pivotally connecting the links to the frame and constituting means in connection with said plates and links whereby the movement of the 10 holder can be varied with respect to the varied cutting stroke of the knives.

2. A wood working machine comprising a frame, a plurality of transversely extending knives fixed to a rotatable head, a rotatable 15 and transversely extending shaft carrying said head, a longitudinally extending and longitudinally and vertically shiftable work holder arranged in operative relation with respect to said knives, a plurality of links piv- 20 otally connected at their upper ends to said holder, the apertures in one link being in alinement with the apertures in the other link, a plurality of apertured plates carried by the frame, the apertures in said plates be- 25 ing in alinement with the apertures in the links, and an adjustable means extending through the links and plates for pivotally connecting the links to the frame and constituting means in connection with said plates and links whereby the movement of the holder can be varied with respect to the varied cutting stroke of the knives, said adjustable means arranged at one side and below the axis of said shaft.

3. A wood working machine comprising a frame, a plurality of transversely extending knives fixed to a rotatable head, a rotatable and transversely extending shaft carrying said head, a longitudinally extending and 40 longitudinally and vertically shiftable work holder arranged in operative relation with respect to said knives, a plurality of links pivotally connected at their upper ends to said holder, the apertures in one link being 45 in alinement with the apertures in the other link, a plurality of apertured plates carried by the frame, the apertures in said plates being in alinement with the apertures in the links, an adjustable means extending through the links and plates for pivotally connecting the links to the frame and constituting means in connection with said plates and links 50 whereby the movement of the holder can be varied with respect to the varied cutting stroke of the knives, and means connected to the holder during the feed thereof for retaining the holder elevated.

4. A wood working machine comprising a frame, a plurality of transversely extending 60 knives fixed to a rotatable head, a rotatable and transversely extending shaft carrying said head, a longitudinally extending and longitudinally and vertically shiftable work holder arranged in operative relation with

respect to said knives, a plurality of links 65 pivotally connected at their upper ends to said holder, the apertures in one link being in alinement with the apertures in the other link, a plurality of apertured plates carried by the frame, the apertures in said plates be- 70 ing in alinement with the apertures in the links, an adjustable means extending through the links and plates for pivotally connecting the links to the frame and constituting means in connection with said plates and links 75 whereby the movement of the holder can be varied with respect to the varied cutting stroke of the knives, said adjustable means arranged at one side and below the axis of said shaft, and means connected to the holder 80 during the feed thereof for retaining the holder elevated.

5. A wood working machine comprising a frame, a plurality of transversely extending knives fixed to a rotatable head, a rotatable 85 and transversely extending shaft carrying said head, a longitudinally extending and longitudinally and vertically shiftable work holder arranged in operative relation with respect to said knives, a plurality of links 90 pivotally connected at their upper ends to said holder, the apertures in one link being in alinement with the apertures in the other link, a plurality of apertured plates carried by the frame, the apertures in said plates be- 95 ing in alinement with the apertures in the links, an adjustable means extending through the links and plates for pivotally connecting the links to the frame and constituting means in connection with said plates and links 100 whereby the movement of the holder can be varied with respect to the varied cutting stroke of the knives, and means carried by the holder for gaging the work with respect to the varied cutting stroke of the knives. 105

6. A wood working machine comprising a plurality of transversely extending revolving knives, a longitudinally extending and longitudinally and vertically shiftable work holder, and means for varying the longitudinal 110 as well as the vertical movement of the work holder.

7. A wood working machine comprising a plurality of transversely extending revolving knives, and a longitudinally extending and 115 longitudinally and vertically shiftable work holder arranged in operative relation with respect to the knives and adapted when shifted in one direction to position the work in the path of the knives.

In testimony whereof I have hereunto set my hand in presence of two subscribing witnesses.

ROBERT P. DE REMER.
